COMBINATION SPRAY DEFLECTOR AND POINT GUARD FOR CAN OPENERS

Robert W. Waterhouse, Wilmette, Ill.

Application April 22, 1952, Serial No. 283,669

5 Claims. (Cl. 30—16)

1

This invention concerns a reversible attachment for can openers of a specified general type, and more particularly relates to a device of this nature which in one position on the can opener serves as a deflector of spray emitted from the can when perforated by the point of the can opener, while in a different position on the can opener, serves as a protective guard covering the perforating point of the can opener to prevent injury to persons when the can opener is being handled or is not in use. The invention is herein illustratively described in its presently preferred form as shown in the accompanying drawings, but it should be understood that certain modifications may be made therein without departing from the essentials of the invention.

The general type of can opener to which the invention appertains is typified by that disclosed in Sampson et al. Patent No. 1,996,550, April 2, 1935, or by that shown in Mumaugh Patent No. 2,080,090 of May 11, 1937, for example. A can opener of the type referred to is characterized by an elongated bar-like handle preferably of uniform flat cross section throughout its length, the handle strip terminating in an operating head comprising a tapered perforating point inclined to the plane of the handle and a pivot hook generally intermediate the handle and the perforating point. The pivot hook engages under the rim of the can to permit forcing the perforating point to penetrate the cover of the can as leverage is applied by raising the handle about its rim pivot. Various devices, including that shown in the Mumaugh patent cited above, have been proposed for catching or deflecting the spray erupting from the initial puncturing of a beer can, for example, when that general type of can opener is used. Some of these attachments have been made as fixed or integral parts of the can opener, whereas others have been of a detachable nature. The present invention relates to an improved device of the latter nature serving the dual purpose of a spray shield in one position on the can opener and a protective point guard in another position on the can opener.

Another object of the invention is a combination spray shield and protective point guard which will be inexpensive to manufacture and extremely compact for packing and shipping purposes. In this latter connection, it is also an object to provide a device of that character which, before application to the can opener, assumes a substantially flat form, readily conducive to handling and packing in large numbers, yet upon application to the can opener in correct position

2

thereon automatically accommodates itself to the latter's shape in order to perform the intended function.

5 A more specific object of the invention is a combination spray shield and protective point guard for such can openers which may be manufactured from a simple blank form cut out of thin, flexible material such as resilient sheet metal or relatively stiff, yet resiliently flexible, plastic sheet material, hence may be cut and formed with inexpensive dies and associated equipment.

10 In brief terms, the improved can opener attachment herein disclosed comprises an attachment collar which slips over the butt end of the bar-like handle of the can opener and may be slid therealong toward the operating end thereof in order to position a spray shield carried by this collar in the correct position relative to the operating head of the can opener. This spray shield is preferably in the form of a flat extension of one side of the slide collar which extension projects therefrom endwise of the handle and overlies the operating head of the can opener on the side thereof opposite the perforating point. In the operative spray deflecting position of the device on the can opener, the shield portion extends approximately in the plane of the can opener handle whereas the perforating point is inclined rather steeply in relation to that plane, so that a dihedral pocket is formed into which the spray and squirting liquid is expelled from the can perforation to impinge the underside of the shield and be thus deflected thereby 15 away from the person using the can opener. Side flaps, normally folded toward each other from opposite side edges of said flat shield portion to lie close alongside the under or inner face thereof, are sprung apart into substantial perpendicularity to the shield portion automatically as an incident of sliding the device along the can opener handle into operative position thereon, such flaps being raised and wedged apart by deflection of their forward edges by sliding contact 20 with opposite side edges of the inclined operating head of the can opener as the attachment device is slid into operative position thereon. Such side flaps when thus extended or sprung apart serve as auxiliary deflecting elements cooperating with the main shield portion and the inclined operating head of the can opener to cover the opposite sides of the dihedral pocket formed between these latter two elements, so as to increase the coverage of the shield and 25 also minimize lateral splashing of squirting liquid 30 35 40 45 50 55

and spray impinging the under side of the shield portion.

While the major features or elements comprising the improved attachment device comprise, as thus broadly described, the attachment collar, the flat shield portion and the resiliently erectible side flaps thereon, the invention also includes certain secondary features related thereto. For example, it is preferred that the projecting end of the shield portion be materially tapered or pointed in general conformity with the shape of the perforating point end portion of the can-opener over which it lies as a spray deflecting shield, and that the forward edges of the side flaps, namely those nearest the pointed end of the shield portion, be likewise inclined to the longitudinal axis of the device such that when the article is being stamped or otherwise cut in blank form out of sheet material, such forward edges will lie in straight-line continuation of the convergent side edges of the tapered point of the shield and thereby simplify cutting dies as well as minimizing waste material by omission of unnecessary protrusive corners.

Moreover, the opposite or rearward edges of the side flaps are preferably cut at a reverse incline to the leading edges thereof so that when the attachment device is installed in operative spray deflecting position on the can opener, these rearward edges will not receive interference from the rim of the can engaged.

When the can opener is put away or is not in use, the novel attachment device may be slid off the handle, inverted, and then slid back along the handle once again until, in this case, the flat shield portion slides up and over the perforating point of the can opener to act as a protective point guard, the inherent flexibility of the sheet material out of which the attachment device is manufactured permitting the necessary deflection of the shield portion in order to cover the point of the holder, just as such flexibility permits erection of the side flaps in the reversely installed position of the device on the can opener.

The foregoing and other features, objects and advantages of the invention including certain details of the preferred form thereof will now become more fully evident by reference to the accompanying drawings.

Figure 1 is a top view of the novel attachment device for can openers of the type generally described herein.

Figure 2 is a top perspective view of the device.

Figure 3 is a similar bottom perspective view of the same.

Figure 4 is a bottom perspective view of the device installed as a spray shield on a can opener.

Figure 5 is a side view illustrating operation of the can opener and spray shield as the top of a beer can, or the like, is being initially perforated.

Figure 6 is a side view of the attachment device installed as a protective point guard on such a can opener.

As illustrated in the drawings the attachment device comprises the slide collar 10 or equivalent retentive slide element formed to slip over the butt end of and slide along the flat, bar-like handle *h* of the can opener (Figure 4). In cutting the blank for the slide collar 10 out of sheet material, it will be evident that two tabs 10a and 10b are formed which are interconnected by the intermediate portion 10c, which tabs are

subsequently folded toward each other and along one face of the portion 10c in order to retentively engage the can opener handle *h* as shown. The flat shield portion 12 constitutes an endwise projection of the sheet material in the collar intermediate portion 10c (Figure 2), while the side flaps 14 and 16 constitute side projections or tabs on the body of sheet material in the shield 12 in blank form. These flaps or side projections are folded inwardly toward each other and closely along side one face of the shield 12 (Figure 3) when the attachment device is formed and ready for installation on the can opener.

Preferably the flat shield portion 12 tapers endwise to a point, its convergent edges 12a and 12b defining an angle between them which is approximately equal to the taper angle of the perforating point of the can opener, which in the usual case is in the vicinity of 60°. In the blank form of the attachment device, the forward edges 14a and 16a of the respective flaps 14 and 16 preferably lie in straight-line continuation of the convergent shield edges 12b and 12a, respectively, for simplification of the cutting die and because there is no necessity for these edges 14a and 16a to be more nearly at right angles to the longitudinal axis of the device, which would require additional material to be used unnecessarily in the blank.

The inner edges or tips 14b and 16b of the respective flaps when folded are slightly separated from each other although they can be made to meet if desired. The remaining or rearward edges 14c and 16c of the respective flaps, namely those edges opposite the edges 14a and 16a, respectively, are preferably inclined oppositely thereto so as to converge inwardly relative to these latter edges, and extend in a straight line from the edges 14b and 16b to the fold lines of the respective flaps on shield portion 12. The opposite edges 12c and 12d of the base or neck of the shield 12, namely where it connects with the collar 10, are preferably straight-line continuations of the flap edges 14c and 16c, respectively, in the blank form, and the width of the shield across its base is preferably less than its general width so as to insure that when it is bent or deflected in relation to the slide collar, the bend will take place mainly at the base so that there will be no buckling tendency in the shield and there will be no undue resistance to bending.

Figure 4 illustrates the installed position of the attachment device on the general type of can opener of interest herein. The operating head of this can opener terminates in the tapered perforating point *p* inclined to the plane of the handle *h* in the usual manner. With the attachment slide collar 10 slipped over the butt end of the handle *h* the flaps 14 and 16 likewise embrace the handle, and the attachment device is slid, point first, endwise along the handle toward the operating head of the can opener. The device is thus advanced along the handle until the flap edges 14c and 16c are past the can opener anchor hook *a* so that when the anchor hook is lodged beneath the rim of the can (Figure 5) these edges will clear the upper edge of the rim, initially at least, during the can-opening operation. As the attachment device is advanced to approach this installed or operative position on the can opener, the leading edges 14a and 16a of the flaps ride down the inclined opposite side edges *o* of the can opener's operating head and undergo a wedging action. The flaps are

thus progressively sprung apart and erected alongside the operating head edges σ' as the attachment device approaches installed position, and in that position such flaps function as spray shields and as splash deflectors, covering the sides of the reentrant dihedral pocket formed between the flat shield portion 12 of the attachment device and the upper side of the operating head of the can opener (Figure 5). It will likewise be noted that in the installed position of the device the main shield portion 12 thereof generally overlies the area on top of the can at which the perforating point p first punctures it. Thus the shield 12 is directly in the path of emitted liquid, gas and spray to protect the user from the squirting liquid.

When the can opener is ready to be put away or stored, the attachment device is simply slid off the handle h , inverted and slid back along the handle to the position shown in Figure 6, in which the tip portion of the shield 12 covers the perforating point p of the can opener and thereby serves as a protective guard thereon.

Thus there is provided a combination spray shield and protective point guard for a can opener of the general type indicated which constitutes a very inexpensive and simple device capable of being stored very compactly and conveniently in large numbers without likelihood of damage, and which is flat so it can be sealed and mailed in paper envelopes and otherwise conveniently packaged, or handled. Being capable of manufacture out of thin semi-rigid, resiliently flexible plastic material, the device, although possessed of a number of edges and one or more points, is nevertheless not at all likely to cut the handler and is extremely light in weight. This is not to say, however, that the device could not be manufactured from resilient sheet metal, as that possibility is certainly to be recognized, although is not considered as important or advantageous as plastic sheet material. It is likewise pointed out that the specific shape and exact form of the attachment device as herein described and illustrated in the accompanying drawings is obviously not the only shape which it may be given, as certain of the details thereof are dictated solely by convenience and preference.

I claim as my invention:

1. The attachable spray shield device for a can opener generally of the type comprising an elongated flat bar-like handle terminating in an operating head, said operating head being tapered to a perforating point inclined relative to the handle and said operating head carrying a hook member intermediate such perforating point and the handle to engage beneath the rim of a can to be opened by said can opener, said attachable shield device comprising a collar portion formed to retentively engage the can opener handle and slide therealong for adjustable positioning relative to the operating head, a substantially flat shield portion carried by said collar member projecting therefrom generally endwise of the handle along one side of such handle, said shield portion being of such size and shape as, when advanced into operative position overlying

the operating head of the can opener, to intercept spray and liquid squirting from the can punctured by the perforating point, said spray shield defining in conjunction with one side of the operating head a dihedral shaped pocket, and flap members resiliently secured to opposite sides of said spray shield portion and normally folded toward one another alongside one face of said shield portion, while embracing the can opener handle when advanced therealong toward the operating head, said flap members being engaged by, and sprung apart along opposite sides of, the operating head by sliding approach of the attachment device into operating position thereof along the handle, to cover the sides of such dihedral pocket and thereby catch spray and minimize lateral splashing of liquid impinging said spray shield portion.

2. The attachable spray shield device defined in claim 1, wherein the shield portion of the device is normally substantially coplanar with one side of the collar portion and is resiliently supported thereby to permit deflection of such shield portion out of that plane effected by sliding of such shield portion along the face of the inclined perforating point of the can opener during advance of such device, in inverted position on the can opener handle, toward the operating head, thereby permitting such shield portion to protectively cover the tip of the perforating point.

3. The attachable spray shield device defined in claim 1, wherein the collar portion, spray shield portion and flap members are formed integrally of plastic sheet material possessed of form-retaining stiffness and resilience.

4. The attachable spray shield device defined in claim 3, wherein the end of the operating head remote from the handle is tapered and the forward edges of the flap members lie in straight-line continuation of the opposite convergent side edges of such tapered point in the blank form of the device.

5. An attachment device for can openers, comprising a collar portion having a generally flat side, a substantially flat shield portion projecting from one edge of said collar portion side in substantially coplanar relation thereto and of a width approximately equal to the width of said collar portion side, and flap portions joined to opposite edges of said shield portion each of a width less than the width of said shield portion and normally folded along one face thereof toward each other but being swingable away from such folded positions into positions projecting transversely of said flat shield portion from its opposite edges.
